UNITED STATES PATENT OFFICE.

FRANZ SKAUPY, OF BERLIN, GERMANY, ASSIGNOR TO DEUTSCHE GASGLÜHLICHT AKTIENGESELLSCHAFT (AUERGESELLSCHAFT), OF BERLIN, GERMANY, A CORPORATION OF GERMANY.

ELECTRIC GAS OR VAPOR LAMP.

1,291,209.

Specification of Letters Patent. Patented Jan. 14, 1919.

No Drawing.

Application filed June 9, 1916. Serial No. 102,768.

To all whom it may concern:

Be it known that I, FRANZ SKAUPY, a citizen of the Empire of Austria-Hungary, and resident of Berlin, Germany, have invented certain new and useful Improvements in Electric Gas or Vapor Lamps, of which the following is a specification.

My invention relates to lamps in which illumination is produced by the action of 10 electrical currents upon gases or vapors. The new and useful feature of my invention consists therein, that such an electric gas or vapor lamp adapted to be operated by arc light discharges contains, besides the gas or 15 vapor made luminous by the passage of current, an inert gas or a mixture of gases not essentially taking part in the illuminating action and which is of such a high pressure that the arc is distinctly contracted 20 either alone or after being mixed together with the luminous vapor or gas.

As inert gas, for instance a rare gas of the atmosphere may be used. Pure argon as 25 inert gas has given the most satisfactory results on account of its excellent conductivity and its comparatively low price. As luminous substances the vapors of easily volatile metals, or of metalloids and their compounds especially the halogen-compounds 30 may be used. These vapors may be produced by the vaporization of the cathode or they may enter the path of the current from any other place, for instance from the anode.

The high pressure of the inert gas is 35 chosen in conformity with the luminous substance. In lamps using mercury as illuminating vapor a substantial contraction of the arc is obtained by using a pressure of higher value, for instance of 100 mm. argon, while 40 in the case of employing salt vapors as luminous substance, for instance the chlorid of zirconium, a pressure of about 3 mm. argon is already sufficient.

The lamps constructed according to my 45 invention present, compared with the hitherto known lamps, many advantages. The high gas-pressure existing in the lamp produces a comparatively high potential fall taking place substantially at the moment of 50 lighting the lamp. There results a high watt-load of the lamp per unit of length, even with currents of medium intensity, which facilitates the rapid vaporization of

the substance serving to produce the luminous action. A further advantage is gained 55 in that the arc passes from the anode to the cathode in the shape of a column, having a narrow cross-section, without touching the walls of the tube, so that consequently the 60 walls of the tube remain comparatively cold contrary to the known mercury-high-voltage lamps in which the high pressure can only be maintained by high temperatures of the walls of the tube. This fact permits the 65 use of glass whereas with the above-mentioned mercury-lamps only quartz may be employed. As the path of current is entirely clear of the walls of the tube, the 70 walls are not at all or not appreciable chemically attacked by the particles of vapor. This is of the highest importance especially in the case of lamps containing vapors of the alkali-metals, because the vapors of these lamps develop even at a low concentration 75 a considerable luminous power with the high temperature of the high-pressure arc.

If mercury vapor is employed as luminous substance in a lamp according to my invention, the troublesome high intensity of current taking place in the known systems of high-pressure mercury lamps during the burning-in period is dispensed with. There is a further advantage that a low partial mercury pressure exists in the gas mantle 80 surrounding the arc, while in the usual high-pressure mercury lamps just the most efficacious fraction of the ultraviolet radiation, namely the line $2536 \mu \mu$ is absorbed and 85 made inoperative by the concentrated vapor 90 inclosing the arc.

The lighting of the lamps is effected in the well known manner, for instance by producing a high-voltage impulse by means of a vacuum-interrupter and a self-induction. 95

What I claim as my invention and desire to secure by Letters Patent is:—

1. A lamp of the class described comprising a receptacle which contains both a substance adapted to conduct the current and to 100 be made luminous thereby and a substantially inert gas which does not appreciably share in the production of luminous effects, said inert gas being at such high pressure that the light column is contracted in cross 105 section and spaced away from the walls of the receptacle.

2. A lamp of the class described comprising a receptacle which contains both a substance adapted to conduct the current and to be made luminous thereby and a rare gas of the atmosphere at relatively high pressure said rare gas not being adapted to share appreciably in the production of luminous effects.
3. A lamp of the class described comprising a receptacle which contains both a substance adapted to conduct the current and

to be made luminous thereby and argon at such high pressure that the light column is contracted in cross section and spaced away from the walls of the receptacle.

In testimony whereof, I have hereunto set my hand.

FRANZ SKAUPY.
